CLAIM

The ornamental design for a child safety lock, as shown and described.

DESCRIPTION

FIG. 1 is a first perspective view of a child safety lock showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of the child safety lock, shown in an alternate configuration of use; and,

FIG. 10 is a perspective view of the child safety lock, shown in an environment of use.

The broken lines shown in FIG. 10 are for purposes of illustrating environmental subject matter only and forms no part of the claimed design; the additional broken lines shown in FIGS. 1-10 are for purposes of illustrating portions of the child safety lock that forms no part thereof.

1 Claim, 10 Drawing Sheets(56)
